Primary Examiner — Angela J Lee

(57) **CLAIM**

The ornamental design for a tablet and cell phone support system, as shown and described.

DESCRIPTION

FIG. 1 is an exploded perspective view of a tablet and cell phone support showing my new design;

FIG. 2 is an exploded side view; opposite side view is a mirror image thereof;

FIG. 3 is an exploded back view thereof;

FIG. 4 is an exploded front view thereof;

FIG. 5 an exploded top view thereof, where the shaded surfaces are complementary hook and loop surfaces;

FIG. 6 is an exploded bottom view thereof, where the shaded surfaces are complementary hook and loop surface; and,

FIG. 7 is a perspective view of a tablet and cell phone support system showing my new design.

1 Claim, 6 Drawing Sheets

FIG. 2

FIG. 3

FIG. 4
